CENTER PUNCH

Emil F. Hager, Queens Village, N. Y.

Application April 5, 1945, Serial No. 586,677

6 Claims. (Cl. 164—123.5)

1

This invention relates to center punches and more particularly to a tool for making impressions in metal or other relatively hard bodies.

In precision tool and watch manufacture, particularly in the making of small sized watches and delicate instruments it is important that impressions be made in predetermined relation and with such accuracy that the aid of the microscope is usually necessary to make adjustments from one impression point to the next. A microscope, for example, is mounted on a standard in conjunction with an arm for supporting the center punch. A pattern is placed under the microscope and the work to be marked with impressions is placed under the punch in a corresponding position. The table or other support upon which the pattern and work are supported is then adjusted from one marking position to the next, the degree of adjustment being determined by viewing the pattern through the microscope. In each such position the center punch is actuated to make the desired impression on the work.

There are a number of known center punches that may be used for this purpose but in each case the punch must be cocked by exerting force against a spring or other punch actuating and/or tripping mechanism thereby transmitting the cocking force to the standard or other means supporting the punch and the microscope. This transmission of force, of course, even in the case of a very sturdy standard tends to bend or alter the supporting structure and vary the alignment of the center punch relative to the work and the microscope in its relationship with respect to the pattern. This variation even though very slight, causes error in the impression marking. For some types of work such error may be permissible but in small precision instruments and delicate watches such error even though slight cannot be tolerated.

It is an object of this invention to provide a center punch of simple construction that overcomes the above mentioned difficulties.

Another object of the invention is to provide a center punch or other impression marking tool capable of being cocked without transmission of the cocking force to the means supporting the punch or tool.

A further object of the invention is to provide a punch or other impression marking tool capable of being cocked to any one of a plurality of different positions for exertion of different impression exerting forces.

A feature of the invention is its simplicity of construction. The punch according to this invention has a simple hammer arrangement which is entirely free of springs and other mechanism that would tend to exert force during recocking actions to the body of the punch or to the means sup-

2

porting the punch. The hammer is arranged to be elevated by a simple lifting action to any one of a plurality of different positions from which it may be released by a slight touch to effect punch exerting force.

The above and other objects and features of the invention will be better understood upon consideration of the following detailed description in connection with the drawings, in which:

- 10 Fig. 1 is a plan view of the center punch and of the means for supporting the punch, and
 Fig. 2 is a view in vertical elevation of the punch and its supporting means with the punch shown in section as viewed along line 2—2 of Fig. 1.
 15 The punch 10 of my invention is shown supported on a standard 11 by means of a bracket 12 which is adjustably secured on the standard by a clamp 13. The punch 10 is adjustably held on the bracket 12 by clamp 14. The punch 20 includes a tubular body or member 15 which threadably receives a punch supporting end piece 16 having a center bore 17 which contains upper and lower hardened bushings 18 and 20. The impression forming punch or tool 21 is slidably received in the bushings 18 and 20, the tool having a pointed punch or other suitably shaped structure 22 at its lower end and an enlarged head portion 23 at its upper end. The head portion preferably includes a flange 24. Between the flange 24 and the end piece 16 is disposed a spring 25. The end piece 16 has threaded thereon a cylindrical guide member having an end flange 27 against which the flange 24 of the head 23 is normally urged by the spring 25, thereby holding the tool 21 in retracted position.

To the upper end of the tubular body member 15 is threadably secured a top member or plug 28 which is provided with an axial opening through which extends the stem 29 of a hammer 30. The hammer is substantially cylindrical for free sliding contact within the hollow body member 15. The hammer includes one or more grooves 31 for passage of air from one end to the other of the member 15 when the hammer is moved. The stem 29 is provided with a plurality of spaced notches 32 whereby the hammer may be retained in any one of a plurality of different elevated positions by selective engagement therewith of a catch lever 34 pivotally supported on vent screw 33. The upper end of the stem is provided with a thumb piece 35 by which the hammer may be easily lifted.

It will be clear from the foregoing description that the hammer 30 may be cocked to any desired elevated position by merely lifting on the thumb piece 35 and engaging the desired notch 32 with the catch 34. This operation avoids or at least greatly minimizes the transmission of any positive force to the supporting bracket 12 and stand-

ard 11 which supports the punch. There are no springs or other mechanism against which the hammer must be forced in order to elevate it to a desired cocked position. The hammer is released by a slight pivotal movement of the catch lever 34. The hammer has a hardened head element 36 which engages the head 23 of the impression forming tool 21. The spring 25 cushions the shock and insures normally retracted position for the tool 21.

While I have disclosed my invention in connection with a specific embodiment and in connection with bracket 12 and standard 11 it should be understood that the punch may be used with other supporting arrangements and the details of the punch may also be varied without departing from the invention. It should therefore be clearly understood that this embodiment is shown and described by way of example only and not as a limitation of the scope of the invention as set forth in the objects and the appended claims.

I claim:

1. A center punch comprising a hollow body, means resiliently supporting an impression forming tool at the lower end of said body, a hammer disposed in said hollow body, a stem extending upwardly from said hammer and protruding out of the upper end of said body by which said hammer may be lifted to a cocking position for release to produce a hammer blow on said tool proportional to the elevated position of said hammer, and means for selecting different predetermined elevated positions from which said hammer may be released, said body, said hammer and said lifting means having clearance for vertical movement of said stem and hammer to minimize transmission of the lifting force to said body.

2. A center punch comprising a hollow body, means resiliently supporting an impression forming tool at the lower end of said body, a top member for said body, said top member having an axial opening therethrough, a hammer loosely disposed in said body, a stem connected to said hammer and extended upwardly loosely through said axial opening by which said hammer can be freely lifted in said body, said stem having a notch, and a catch carried by said top member to releasably engage with said notch to retain said hammer in elevated position whereby release of said hammer by actuation of said catch produces a hammer blow on said tool proportional to the elevated position of said hammer.

3. A center punch comprising a hollow body, means resiliently supporting an impression forming tool at the lower end of said body, a hammer disposed in said hollow body, a stem connected to said hammer and extended upwardly from the top of said body by which said hammer can be freely lifted in said body, said stem having a plurality of spaced notches, and a catch pivotally mounted at the top of said body to releasably engage said notches to retain said hammer in desired elevated positions, whereby release of said hammer by actuation of said catch produces a hammer blow on said tool proportional to the elevated position of said hammer, said body, hammer and said stem having clearance for vertical movement of said stem and hammer to insure a free lifting movement of said hammer, thereby minimizing transmission of lifting force to said body.

4. A center punch comprising a tubular body, an impression forming tool in said body, a top

member for said tubular body, an axial opening in said top member, a hammer disposed in said tubular body, a stem connected to said hammer and extended upwardly through said axial opening, said stem having a plurality of spaced notches and a catch pivotally mounted at the top of said body to releasably engage said notches to retain said hammer in desired elevated positions, whereby release of said hammer by actuation of said catch produces a hammer blow on said tool proportional to the elevated position of said hammer, said body and said stem having clearance for vertical movement of said stem and hammer to minimize transmission to said body of force exerted on said stem to lift said hammer.

5. A center punch comprising a tubular body adapted to be held in a substantially vertical position, an end piece for the lower end of said tubular body, said end piece having an axially disposed bore therein with bushings at opposite ends of the bore, an impression forming tool slidably engaged in said bushings, said bushings serving to maintain said tool in truly aligned relation throughout its movement, means for resiliently elevating said tool, a hammer in said tubular body, and means for lifting said hammer to a position for release to produce a hammer blow on said tool proportional to the elevated position of said hammer, said means for resiliently elevating said tool including a member secured at the lower end of said body, said member having an inwardly disposed portion at its upper end, said tool having abutment means to engage said portion, and a spring disposed between said end piece and said abutment means to normally urge the latter against said portion.

6. In a punching machine, a tubular body, a standard, a bracket carried by said standard and extending outwardly therefrom to support said tubular body in substantially vertical position, means resiliently supporting an impression forming tool at the lower end of said body, a hammer disposed in said body, means including a stem connected to said hammer and extended through the upper end of said body for freely lifting said hammer to a position for release to produce a hammer blow on said tool, said body, said hammer and said lifting means having clearance for vertical movement of said stem and hammer to insure a free lifting movement of said hammer, thereby minimizing transmission to said bracket and standard of the force required to lift said hammer.
